(57) **CLAIM**

The ornamental design for an underwater exhaust system that acts as a bubble diverter, as shown and described.

DESCRIPTION

FIG. 1 is a perspective view of the underwater exhaust system that acts as a bubble diverter showing my new design;

FIG. 2 is a front view thereof;

FIG. 3 is a left side view thereof;

FIG. 4 is a right side view thereof;

FIG. 5 is a back view thereof;

FIG. 6 is a top view thereof; and,

FIG. 7 is a bottom view thereof.

In the drawings, the broken lines depict portions of the underwater exhaust system that acts as a bubble diverter that form no part of the claimed design.
